UNITED STATES PATENT OFFICE.

CHARLES E. BAESE, OF WILMINGTON, ILLINOIS.

FEED-TROUGH FOR POULTRY.

No. 856,564.

Specification of Letters Patent.

Patented June 11, 1907.

Application filed December 5, 1906. Serial No. 346,489.

To all whom it may concern:

Be it known that I, CHARLES E. BAESE, a citizen of the United States, residing at Wilmington, in the county of Will, State of Illinois, have invented certain new and useful Improvements in Feed-Troughs for Poultry; and I do hereby declare the following to be a full, clear, and exact description of the invention, such as will enable others skilled in the art to which it appertains to make and use the same.

This invention has relation to feed-troughs generally, and more particularly to feed troughs or hoppers for poultry.

It is the object of the invention to provide such improvements in the kind of devices mentioned as will tend to prevent the waste of feed, secure cleanliness of the latter in the trough, prevent fowls from roosting upon the trough, and in general to facilitate the presentation, whether of a large or small amount, at a line or point where it may be readily reached by the fowls.

The invention is clearly disclosed in the contrivance portrayed in the annexed drawings, forming a part of this specification, in view of which it will first be described with respect to its construction and mode of operation and employment, and then be pointed out in the subjoined claims.

Of the said drawings—Figure 1 is a side elevation. Fig. 2 is an end elevation. Fig. 3 is a longitudinal section. Fig. 4 is a transverse section.

Similar numerals of reference designate similar parts or features, as the case may be, wherever they occur.

In the drawings, 10 designates the trough proper, which for the sake of example, merely, may be considered as being four feet in length and six inches wide, and six inches in depth, though the size may be varied to suit circumstances. The trough is supported at each end by divergent legs 11 of inverted V shape, the apexes 12 of which extends above the ends of the trough and are provided with bearings, 13, for the trunnions or pins 14 extending from the ends of a longitudinally fluted rail 15 supported longitudi-

nally over the center of the trough. The rail 15 will be supported sufficiently high above the top of the trough to permit fowls to easily pass their heads therebetween the rail sides of the trough to eat from the trough, and yet said rail will be arranged on a line sufficiently low to prevent fowls from roosting on the sides of the trough. In addition to this the fluted character of the rails as well as its bearings in the apexes of the legs will insure its turning so that a fowl cannot balance itself upon the rail as a perch to roost thereon. These features in the construction of the invention tend to keep the food in the trough free from being befouled as would be likely to be done if poultry were allowed to roost or perch upon the sides of the trough.

16 designates a partition in the trough setting off a box 17 at one end for the reception of chopped meat while the longer or larger portion 18 of the box is designed for grain feed. Each trough or box is provided with a screen 19 secured on the bottom of the frame 20 which latter fits loosely in the box. The mesh or openings in the screen will be sufficiently large to permit fowls to eat grain or meat food through the same when the screens are placed on the top of the food as it is designed they shall be. As the food is pecked away through the meshes of the screen the latter acting as followers will be lowered as the food is lowered and at all times act as a preventive to the waste of the latter.

It will be noted from the description hereinbefore given, that in addition to preventing waste of food, and cleanliness of the same great economy is subserved in not only preventing absolute waste but keeping the feed at all times in condition so that it may be eaten by the fowls.

What is claimed is—

1. A feed-trough for poultry provided with a rotary rail supported above the trough, intermediate of the plane of its sides.
2. A trough-feed for poultry provided with a rotary and longitudinally fluted rail supported above the trough intermediate of the plane of its sides.
3. A feed-trough for poultry provided with

a screen-like follower adapted to be placed on top of the food in the trough, the openings through the screen being sufficiently large to permit the fowls to peck the food there-
5 through.

4. A feed-trough for poultry comprising the trough proper, legs of inverted V form secured to the ends thereof, the apexes of said legs extending above the top of the box, and

a rotary rail having journaled ends supported in bearings in said apexes.

In testimony whereof, I affix my signature, in presence of two witnesses.

CHARLES E. BAESE.
